DESIGN FOR A COAT

Jacob A. Silverman, Brooklyn, N. Y.

Application August 25, 1939, Serial No. 86,881

Term of patent 3½ years

To all whom it may concern:

Be it known that I, Jacob A. Silverman, a citizen of the United States of America, residing in New York city, in the Borough of Brooklyn, county of Kings and State of New York, have invented a new, original, and ornamental Design for a Coat; of which the following is a specification, reference being had to the accompanying drawing, forming part thereof, wherein,

I claim:

The ornamental design for a coat, substantially as shown.

JACOB A. SILVERMAN.
